(57) **CLAIM**

The ornamental design for a compression assembly to relieve menstrual cramping, as shown and described.

DESCRIPTION

FIG. 1 is a right perspective view of the compression assembly to relieve menstrual cramping;

FIG. 2 is a front perspective view of the compression assembly to relieve menstrual cramping;

FIG. 3 is a right view of the compression assembly to relieve menstrual cramping;

FIG. 4 is a left view of the compression assembly to relieve menstrual cramping;

FIG. 5 is a back view of the compression assembly to relieve menstrual cramping;

FIG. 6 is a front view of the compression assembly to relieve menstrual cramping;

FIG. 7 is a top view of the compression assembly to relieve menstrual cramping; and,

FIG. 8 is a bottom view of the compression assembly to relieve menstrual cramping.

Broken line is included for the purpose of illustrating portions of the article and forms no part of the claimed design.
